ABSTRACT OF THE DISCLOSURE

The treatment of wounds by orally administering a pharmaceutical preparation containing a compound of the formula I

wherein R_1 is hydrogen or alkyl with up to 7 carbon atoms, and R_3 , R_5 and R_6 each independently is hydrogen, alkyl with up to 7 carbon atoms, alkenyl with up to 7 carbon atoms, benzyl, halogeno-benzyl, $(\text{C}_1\text{--C}_7\text{alkyl})\text{-benzyl}$, $(\text{C}_1\text{--C}_7\text{alkoxy})\text{-benzyl}$ or trifluoromethyl-benzyl.

DESCRIPTION OF THE INVENTION

The invention relates to the treatment of wounds which is characterized by orally administering a pharmaceutical preparation containing a compound of the formula I

wherein R_1 is hydrogen or alkyl with up to 7 carbon atoms, and R_3 , R_5 and R_6 each independently is hydrogen, alkyl with up to 7 carbon atoms, alkenyl with up to 7 carbon atoms, benzyl, halogeno-benzyl, $(\text{C}_1\text{--C}_7\text{alkyl})\text{-benzyl}$, $(\text{C}_1\text{--C}_7\text{alkoxy})\text{-benzyl}$ or trifluoromethyl-benzyl.

A residue R_1 , R_3 , R_5 , and R_6 being alkyl with up to 7 carbon atoms and $\text{C}_1\text{--C}_7\text{alkyl}$ in a residue R_3 , R_5 and R_6 being $(\text{C}_1\text{--C}_7\text{alkyl})\text{-benzyl}$ is methyl, ethyl, propyl or isopropyl, and straight or branched butyl, pentyl, hexyl or heptyl bonded in any desired position.

A residue R_3 , R_5 and R_6 being alkenyl with up to 7 carbon atoms is especially for example an allyl and methallyl radical.

Halogen in a halogeno-benzyl radical R_3 , R_5 and R_6 is fluorine, bromine, iodine and especially chlorine.

$\text{C}_1\text{--C}_7\text{alkoxy}$ in a residue R_3 , R_5 and R_6 being $(\text{C}_1\text{--C}_7\text{alkoxy})\text{-benzyl}$ is ethoxy, n-propoxy, iso-propoxy and straight or branched butyloxy, pentyloxy, hexyloxy or heptyloxy and especially methoxy.

The compounds of the formula I are mixtures of anomers or α - or β -anomers.

It has been found that orally administering a pharmaceutical preparation as defined above is helpful for the healing of wounds. Thus, oral administration of a pharmaceutical preparation as defined above results (a) in a stimulation of the formation of granulation tissue, as can be shown in the wound granulation test according to Rudas [Arzneimittel Forschung, 10, 226-229 (1960)] on rats by oral administration of about 1000-2000 mg./kg./day of a compound of the formula I, (b) in an acceleration of the wound diameter reduction, as can be shown in the epithelisation test according to Wilhelmi [Giornale Ital. Chimioter., 1, 111-116 (1954) and Salicylates, In-

2

ternat. Sympos., London, 1962, Churchill LTD, London, 176-185 (1963)] on rats by oral administration of about 1000 mg./kg./day of a compound of the formula I, and (c) in an increase of the wound breaking strength, as can be shown in the tensile strength test according to Sixt et al. [Arzneimittel Forschung, 18, 1460-1462 (1969)] on rats by oral administration of about 300-1000 mg./kg./day of a compound of the formula I.

According to a preferred embodiment of the invention the treatment of wounds is performed by orally administering a pharmaceutical preparation containing a compound of the formula I, wherein R_1 is alkyl with up to 4 carbon atoms, and R_3 , R_5 and R_6 each independently is alkyl with up to 4 carbon atoms, alkenyl with up to 4 carbon atoms, benzyl, halogeno-benzyl, $(\text{C}_1\text{--C}_4\text{alkyl})\text{-benzyl}$, $(\text{C}_1\text{--C}_4\text{alkoxy})\text{-benzyl}$ or trifluoromethyl-benzyl.

Above all to be mentioned is said treatment using a pharmaceutical preparation containing a compound of the formula I, wherein R_1 is alkyl with up to 4 carbon atoms, especially methyl or ethyl, and one, two or all three of R_3 , R_5 and R_6 are benzyl, chloro-benzyl, methyl-benzyl, methoxy-benzyl or trifluoromethyl-benzyl and the remaining are alkyl with up to 4 carbon atoms or alkenyl with up to 4 carbon atoms, especially methyl, ethyl, n-propyl or allyl.

Compounds of the formula I to be especially highlighted are ethyl - 3 - O - n-propyl-5,6-di-O-(4-chlorobenzyl)-D-glucofuranoside and above all ethyl-3,5,6-tri-O-benzyl-D-glucofuranoside.

According to the invention the pharmaceutical preparations as defined above are administered orally to a warm-blooded animal in doses sufficient for improving the healing of wounds. Thus, a warm-blooded animal of about 75 kg. body weight is orally treated with a daily dose of about 400 mg. to about 1200 mg., above all of about 600 mg. to about 1200 mg. of a compound of the formula I, especially one of the above preferably mentioned compound of the formula I. The compound of the formula I is preferably administered in the form of a pharmaceutical preparation as defined above.

According to a preferred method of treatment of wounds a pharmaceutical preparation is orally administered containing as compound of the formula I ethyl-3-O-n-propyl-5,6 - di - O - (4-chlorobenzyl)-D-glucofuranoside or ethyl-3,5,6-tri-O-benzyl-D-glucofuranoside in doses of about 400 mg. to about 1200 mg., especially of about 600 mg. to about 1200 mg. per day of said compounds of the formula I.

Oral administration of a pharmaceutical preparation as defined above can be effected after a wound is created in a warm-blooded animal, e.g. by accident or by operation, but can also be effected before an operation is performed, e.g. up to several days, such as 4 days before an operation is performed.

The pharmaceutical preparations as defined above contain a compound of the formula I either without any carrier or preferably in admixture or conjunction with a pharmaceutically acceptable carrier for liquid or solid preparations.

A pharmaceutically acceptable carrier is for example concentrated milk, a suitable oil, such as olive oil, polyethyleneglycol or carboxymethylcellulose. Such a pharmaceutically acceptable carrier is especially suitable for liquid pharmaceutical preparations.

A pharmaceutically acceptable carrier especially suitable for solid pharmaceutical preparations is for example described in U.S. Pat. 3,594,474. Accordingly, a free flowing granular material which can easily be processed into solid oral administration forms can be obtained in a simple manner if an oily or liquid compound of the formula I is mixed with a film-forming agent and a lower alkanol such as methanol, isopropanol or primarily etha-

nol, worked into a plastic mass with magnesium trisilicate, if desired together with a further absorbent such as colloidal silica or cellulose, especially microcrystalline cellulose, and the mass granulated whilst drying it, for example with warm air.

As film-forming agents there are preferably used those which also act as binding agents, especially shellac, polyacrylic or methacrylic derivatives, especially their esters, carbowaxes, polyvinyl derivatives such as polyvinyl acetates, or primarily polyvinyl pyrrolidone, for example polyvinylpyrrolidone or polyvinylpyrrolidone-polyvinyl acetate copolymers. Further possible film-forming agents are alcohol-soluble or water-soluble cellulose derivatives, especially cellulose acetate-phthalate, hydroxypropyl-methylcellulose, ethylcellulose, ethyl-hydroxyethyl-cellulose, hydroxypropyl-cellulose, carboxymethylcellulose and/or carboxyethylcellulose.

The process is preferably effected by dissolving the film-forming agent in the lower alkanol, mixing the furanoside with this solution, and mixing this solution with the magnesium trisilicate and optionally the adsorbent to give a plastic mass, and drying and granulating the latter in the usual manner. When mixing the solution of the furanoside with magnesium trisilicate, the sugar is adsorbed on the latter.

The film-forming agent is preferably used in a concentration of 0.2 to 20, especially 1-5 and primarily 2-4, parts by weight relative to 10 parts by weight of furanoside. The magnesium trisilicate is used in an amount which permits adsorption of the furanoside, especially in a concentration of 5-20, preferably 8-15 or primarily about 10-12 parts by weight calculated relative to 10 parts by weight of furanoside. The further adsorbent is used in an amount of 1-20, preferably 1-10 and primarily 4-6, parts by weight calculated relative to 10 parts by weight of furanoside.

The granular material obtained is stable for prolonged periods even at a higher temperature, for example 60°, and can be easily processed into any desired oral administration form.

The granular material is suitable for the manufacture of solid oral administration forms such as tablets, push-fit capsules or primarily dragées. These may be obtained in the usual manner.

EXAMPLE 1

10 parts by weight of ethyl-3,5,6-tri-O-benzyl-D-glucouranoside, 10 parts by weight of magnesium trisilicate, 5 parts by weight of colloidal silica and 2.5 parts by weight of polyvinylpyrrolidone (PVP).

The PVP is dissolved in a fourfold amount of alcohol and mixed with the ethyl-3,5,6-tri-O-benzyl-D-glucouranoside. This solution is processed into a paste with the magnesium trisilicate in a suitable apparatus and is kneaded with colloidal silica to give a plastic mass. It is then granulated and dried in the usual manner.

5.45 parts by weight of granular material are mixed with 2.0 parts by weight of starch, 1.7 parts by weight of talc and 0.3 part by weight of magnesium stearate and processed into pressed blanks weighing 585 mg. and containing 200 mg. of ethyl-3,5,6-tri-O-benzyl-D-glucouranoside.

In order to mask the bad taste, the pressed blanks are, after coating with a protective lacquer, converted in the usual manner with sugar into dragées.

The daily oral dose for a warm-blooded animal of about 75 kg. body weight is about 2 to 6 dragées.

EXAMPLE 2

10 parts by weight of preparation of ethyl-3-O-n-propyl-5,6-di-O-p-chlorobenzyl-D-glucouranoside, 14 parts by weight of magnesium trisilicate, 5 parts by weight of colloidal silica and 2.5 parts by weight of polyvinylpyrrolidone.

The PVP is dissolved in the fourfold quantity of alcohol and mixed with the furanoside. This solution is processed into a paste with magnesium trisilicate in a suitable apparatus and kneaded with colloidal silica to give a plastic mass. The mass is granulated and dried in the usual manner.

31.5 parts by weight of granular material are mixed with 0.8 part by weight of starch, 1.55 parts by weight of microcrystalline cellulose, 1.05 parts by weight of talc and 0.15 part by weight of magnesium stearate and processed into pressed blanks of 350 mg.=100 mg. of furanoside.

These cores are given a protective lacquer in the usual manner and then converted into dragées with sugar.

15 The daily oral dose for a warm-blooded animal of about 75 kg. body weight is about 6-12 dragées.

EXAMPLE 3

20 10 parts by weight of ethyl-3,5,6-tri-O-benzyl-D-glucouranoside, 10 parts by weight of magnesium trisilicate, 5 parts by weight of colloidal silica, 0.5 part by weight of polyvinylpyrrolidone, and 2 parts by weight of microcrystalline cellulose.

25 The PVP is dissolved in a fourfold amount of alcohol and mixes with the ethyl-3,5,6-tri-O-benzyl-D-glucouranoside. This solution is processed into a paste with the magnesium trisilicate in a suitable apparatus and is kneaded with colloidal silica to give a plastic mass. It is then granulated and dried in the usual manner.

30 5.45 parts by weight of granular material are mixed with 2.0 parts by weight of starch, 1.7 parts by weight of talc and 0.3 part by weight of magnesium stearate and processed into pressed blanks weighing 585 mg. and containing 200 mg. of ethyl-3,5,6-tri-O-benzyl-D-glucouranoside.

In order to mask the bad taste, the pressed blanks are, after coating with a protective lacquer, converted into dragées with sugar in the usual manner.

40 The daily oral dose for a warm-blooded animal of about 75 kg. body weight is about 6-12 dragées.

What is claimed is:

45 1. A method of treating wounds in a warm-blooded animal which is characterized by orally administering to said animal an effective wound healing amount of a compound of the formula

wherein R_1 is hydrogen or alkyl with up to 7 carbon atoms, and R_3 , R_5 and R_6 each independently is hydrogen, alkyl with up to 7 carbon atoms, alkenyl with up to 7 carbon atoms, benzyl, halogeno-benzyl, $(\text{C}_1\text{---C}_7\text{-alkyl})\text{-benzyl}$, $(\text{C}_1\text{---C}_7\text{-alkoxy})\text{-benzyl}$ or trifluoromethyl-benzyl.

60 2. The method of claim 1, wherein R_1 is alkyl with up to 4 carbon atoms, and R_3 , R_5 and R_6 each independently is alkyl with up to 4 carbon atoms, alkenyl with up to 4 carbon atoms, benzyl, halogeno-benzyl, $(\text{C}_1\text{---C}_4\text{-alkyl})\text{-benzyl}$, $(\text{C}_1\text{---C}_4\text{-alkoxy})\text{-benzyl}$ or trifluoromethyl-benzyl.

65 3. The method of claim 1, wherein R_1 is alkyl with up to 4 carbon atoms, and one, two or all three of R_3 , R_5 and R_6 are benzyl, chloro-benzyl, methyl-benzyl, methoxy-benzyl or trifluoromethyl-benzyl and the remaining are alkyl with up to 4 carbon atoms or alkenyl with up to 4 carbon atoms.

70 4. The method of claim 1, wherein the compound is ethyl-3-O-n-propyl-5,6-di-O-(4-chlorobenzyl)-D-glucouranoside.

75

5. The method of claim 1, wherein the compound is ethyl-3,5,6-tri-O-benzyl-D-glucofuranoside.
6. The method of claim 1, wherein a daily dose of 400-1200 mg. is administered to a warm-blooded animal of about 75 kg. body weight.
7. The method of claim 1, wherein the compound is employed without any carrier.
8. The method of claim 1 wherein the compound is employed in admixture or conjunction with a pharmaceutically acceptable carrier.
